Primary Examiner — Derrick E Holland*Assistant Examiner* — Janice Patyk(74) *Attorney, Agent, or Firm* — Stetina Brunda Garred & Brucker(57) **CLAIM**

The ornamental design for a wireless mobile speaker, as shown and described.

DESCRIPTION

FIG. 1 is a rear perspective view showing the wireless mobile speaker of the present invention;

FIG. 2 is a front perspective view thereof;

FIG. 3 is a top view thereof;

FIG. 4 is a right side view thereof;

FIG. 5 is a front view thereof;

FIG. 6 is rear view thereof;

FIG. 7 is a left side view thereof; and,

FIG. 8 is a bottom view thereof.

The broken lines in the figures illustrate the portions of the design that form no part of the claimed design.

1 Claim, 3 Drawing Sheets(56)
